ABSTRACT: In a calculating machine or the like apparatus having a plurality of vertically movable rack bars arranged in side-by-side parallel relation and accumulator gears cooperating with each of said rack bars, a cam is provided on each accumulator gear, while a first lever to be operated by said cam is provided on one side of each rack bar, and a second lever is connected to the first lever to be operated thereby. When the first lever is lowered by the cam upon rotation of the accumulator gear, the second lever is also lowered by the first lever and pushed by a push rod in its lowered position, whereby the rack bar is lowered and at the same time the second lever of the adjacent rack bar is pushed by the second lever of the first-mentioned rack bar, so that the adjacent rack bar is also lowered, and thus the column is carried.

COLUMN CARRYING MECHANISM IN CALCULATING MACHINE AND THE LIKE APPARATUS

The present invention relates to a column carrying mechanism in a calculating machine or the like apparatus.

In a conventional column carrying mechanism including rack bars and an accumulator, each gear must be revolved one pitch upon completion of one complete revolution of the preceding gear for a lower column, to effect column carrying. This is obviously attained by a column carrying mechanism. When the one pitch motion is transmitted to a gear in an accumulator which is about to complete its full revolution, one pitch motion of a gear in the higher column is further caused, and thus a chain of motion takes place. In this way, the motions of clutches associated with the respective gears are induced successively. In other words, the motion of the rack for an upper column is commenced upon completion of the motion of the rack for a lower column. Therefore, the time required for the completion of a column carrying operation is the sum of the times required for the movement of the individual racks associated with the numerals set. Namely, the conventional column carrying mechanism has the drawback that the time required for the column carrying operation is undesirably long. Such drawback has a bearing on the calculation cycle, making it impossible to increase the speed of said cycle.

In view of the above, the present invention has for its object the provision of a column carrying mechanism which is so designed that all of the racks participating in the column carrying operation are lowered one pitch in the same period of time, whereby the time required for the column carrying operation can be minimized.

According to the present invention, there is provided a column carrying mechanism in a calculating machine having a large number of vertically movable rack bars arranged in side-by-side parallel relation and accumulator gears meshing with said respective rack bars, which comprises a link mechanism which is operated more than about one tooth in the column carrying operation by a cam provided on the higher column side of said gear, and means for lowering the rack bars for the next higher column one tooth from the "0"-position upon engaging only with said operated link mechanism and displacing the same, said link mechanism having a member which, when said link mechanism is operated more than about one-half tooth, causes displacement of all of the link mechanisms for the next higher column relative to said operated link mechanism by engagement therewith and further lowers the rack bar for the column one tooth.

The present invention will appear more clearly from the following detailed description when taken in connection with the accompanying drawings, showing by way of example a preferred embodiment of the invention. In the drawings,

FIG. 1 is a side view of a preferred embodiment of the column carrying mechanism according to the present invention in the state before a gear for the place of 1 and a rack bar for the place of 10 before are placed in motion;

FIG. 2 is a side view of the mechanism showing the positions of a gear for the place of 10 and a rack bar for the place of 100 before the column carrying operation;

FIG. 3 is a side view of the mechanism showing the positions of the gear for the place of 1 and the rack bar for the place of 10 before the column carrying operation;

FIG. 4 is a side view of the mechanism showing the positions of the parts for the place of 1 and for the place of 10 after the column carrying operation; and

FIG. 5 is a view as viewed from the line A-A of FIG. 3.

Referring to FIGS. 1 to 3, numeral 1 designates a rack bar commonly used in a calculating machine, 2 a stopper for a numeral setting carriage (not shown) and 5 a sector which is provided with types 5a and formed with two projections 5b, 5c at the downwardly extending portion thereof. Numeral 3 designates a lowering bar which will move the sector 5 downward by engagement with the projection 5b against the

biasing force of a spring 4. The sector 5 is also provided with a pin 28 which is received in a slot 31 formed in the rack bar 1. A spring 32 has one end anchored to the projection 5c of the sector 5 and the other end to a projection 1a of the rack bar 1.

5 A pair of gears 8 and 9 are rotatably mounted on fixed shafts 6 and 7 respectively in opposed relation to each rack bar 1 for engagement therewith. Each rack bar 1 has a longitudinal slot 1b formed therein, in which is slidably received a fixed cross bar 10 for guiding a vertical movement of said rack bar. On the left side or the higher column side of each rack bar 1 is provided a first lever 11 having teeth 11a and 11b. In the illustrations of FIGS. 1 to 3, the lever 11 for the next lower column relative to the rack bar 1 is shown. These teeth are parallel to teeth 1c of the rack bar 1 and engageable with half-tooth shaped cams 8a and 9a which are provided on one side of the accumulator gears 8 and 9 respectively. The first lever 11 also has teeth 11c and 11d adapted for engagement with the cross bar 10, a projection 15 for engagement with a return bar 21 to be described later, a projection 16 having one end of a spring 17 anchored thereto, the other end of said spring being anchored to a fixed member of the machine, and a projection 18 slidably received in a slot formed in a fixed support plate 19. A second lever 22 is connected to the first lever 11 by a pin 29 and has a roller 23 which can roll on the fixed support plate 19 and engages a cam surface 27 on the underside of the rack bar 1. The second lever 22 is also formed with a projection 25 which is in engagement with a slot formed in the fixed support plate 19. An end 30 of the second lever 22 is provided with a rightwardly extending horizontal tongue 31 at the lower portion thereof and a leftwardly extending vertical tongue 32 at the end extremity. A push rod 33 is located in front of the tongue 32 and caused to move towards the second lever 22 at the end of the downward movement of the rack bar 1 which is caused by the lowering bar 3 as will be described hereinafter. The fixed support plate 19 has a comblike shape and is provided with a tongue 34.

The mechanism constructed as described above will operate as follows: With reference to FIG. 5, let it be supposed that numeral "8" is memorized by a gear 9-1 which is for memorizing a numeral in the place 1 and numeral "8" is also memorized by a gear 9-2 which is for memorizing a numeral in the place of 10, or in other words, numeral "88" is memorized by the respective gears. When numeral "12" is to be added, for example, the cam 9a of the gear which memorized numeral "8," is located above the tooth 11b of the first lever 11.

First of all, numeral "1" is set, whereupon the stopper 2a corresponding to numeral "1" is projected as indicated by the chain line in FIG. 1. The same thing occurs when numeral "2" in the place of 10 is set. Upon setting the machine in motion to perform one cycle of operation, all of the gears 9 are moved to the right all at once to be spaced from the respective rack bars 1 and the lowering bars 3 move upward successively thereafter, so that only the sectors and the rack bars (not shown) for the place of 1 and the place of 10 are allowed to move upward until the projection 1d of each rack bar 1 abuts against the stopper 2a.

Then, each gear 9 is moved to the left and engages the rack bar 1. Thereafter, the lowering bars 3 move downward, whereby the rack bars for the place of 1 and the place of 10 are moved downward, while rotating the respective gears 9 in the direction of the arrow A. FIG. 2 shows the operation for the place of 10. The gear 9-2 for the place of 10 is rotated one tooth incident to setting numeral "1." In this case, the tooth 11b of the first lever 11 is pushed by the rotating cam 9a and the first lever 11 is moved down to the position of FIG. 2. Therefore, the second lever 22, connected to the first lever 11 by the pin 29, is caused to make a pivotal movement about the roller 23 in a clockwise direction, to the position shown.

The gear 9-1 for the place of 1 takes the position shown in FIG. 3. Namely, the first lever 11 is further moved downward by the cam 9a, and as a result, the tooth 11d is disengaged from the cross bar 10 and the lever 11 is tilted as shown under 75 the biasing force of the spring 17. Now, the projection 15 is

located closer to the return bar 21 and the tongue 32 is lowered to a position confronting the push rod 33. As a result of the above-described operation, the tongue 32a of the second lever 22 for the place of 1 is located in the lowest position and the tongue 32b of the second lever 22 for the place of 10 is located in a one-step lowered position as shown in FIG. 5.

Then, the push rod 33 is moved to the left in the direction of the arrow B and pushes the tongue 32a of the second lever 22 for the place of 10 which has been lowered most as shown in FIG. 5. This state is shown in FIG. 4. As a result of the leftward movement of the second lever 22, the tongue 32 of said second lever abuts against the tongue 31a of the adjacent second lever for the place of 100 which has been lowered to an intermediate position, and pushes the same. Thus, both of the second levers 22, 22a are moved to the left and the respective rack bars 1 are allowed to move down one step due to disengagement of the rollers 23 in engagement with the cam surfaces 27 of said respective rack bars. Therefore, the gears for the place of 10 and the place of 100 are rotated one tooth and further the tongues 31 are placed below the tongues 34 of the support plates 19 to hold the respective second levers against upward movement.

All of the second levers for the places other than those mentioned above are held inoperative.

Then, all of the gears 9 are moved to the right to be spaced from the corresponding rack bars and the respective numerals are memorized by the gears 9-2 and 9-3 for the place 10 and the place of 100, with numeral "1" added thereto, that is to say that numeral "100" is memorized. This means that the column carrying has been accomplished. Finally, the bar 33 is moved to the right and the return bar 21 is moved to the right in the direction of the arrow C to return the first lever 11 and the second lever 22 to their original positions. By this step, one cycle of column carrying operation has been completed.

As will be clearly understood from the foregoing, according to the present invention only the rack bar for the column which is to be carried up is lowered one tooth and the rack bar meshing with the gear which memorizes numeral "9" in the higher place is lowered simultaneously, so that the column

carrying can be effected concurrently and the operation time can be shortened.

In the above-mentioned embodiment the first lever 11 has the teeth 11a and 11b. However, the first lever 11 may be provided with a single tooth. In this case the gear 8 and the gear 9 should be engaged alternatively.

What I claim is:

1. A column carrying mechanism in a calculating machine or the like apparatus of the type comprising toothed rack bars (1) and an accumulator comprising gears (8, 9) having cam means (8a, 9a), said mechanism further comprising

a first lever (11) arranged adjacent each rack bar (1) and adapted to engage said cams (8a, 9a) on said accumulator gears (8, 9), said first lever being moved by one of said cams (8a or 9a) as said cam completes its one revolution, a second lever (22) adapted to oscillate vertically under the control of said first lever (11) and having a member (23) in engagement with said rack bars (1), a fixed cross bar (10) extending through a longitudinal slot formed in said rack bar (1), and

a push rod (33) for actuating each second lever (22) when the associated first lever (11) is latched by said fixed cross bar (10) upon being lowered by said cam (8a or 9a) of said gear (8 or 9), said mechanism being operative in such a manner that when the first lever (11) is lowered by the cam (8a or 9a) of the gear (8 or 9), the second lever (22) is brought to a position confronting the push rod (33) and pushed by said push rod (33), whereby only the rack bar (1) associated with said pushed second lever (22) is lowered one pitch and concurrently the column associated with said rack bar is carried.

2. A column carrying mechanism as defined in claim 1, wherein said second lever (22) is provided with a horizontal tongue (31) and a vertical tongue (32), said horizontal tongue (31) being inserted below a fixed part (34) to retain said second lever (22) in position when said second lever is lowered, and said vertical tongue (32) being pushed by said push rod (33) when said second lever (22) is in its lowered position, whereby the adjacent second lever (22) is pushed by said horizontal tongue (31).
